[57] CLAIM

The ornamental design for a lure, as shown and described.

DESCRIPTION

FIG. 1 is a perspective view of my new design for lure illustrated in use on a fish hook;

FIG. 2 is a side view thereof;

FIG. 3 is an end view thereof;

FIG. 4 is a top view thereof; and,

FIG. 5 is a bottom view thereof.

The broken line showing of the environmental structure in FIG. 1 is for illustrative purposes only and forms no part of the claimed design.
